RUSSELL C. JONES, OF BRONXVILLE, NEW YORK, ASSIGNOR TO THE GRISCOM-RUSSELL COMPANY, OF NEW YORK, N. Y., A CORPORATION OF DELAWARE.

DEAERATOR.

Application filed September 4, 1925. Serial No. 54,583.

The present invention relates to deaerating apparatus for steam generating systems and has to do with the furnishing of substantially gas free water to the boilers.

5 Water as supplied to a steam generating plant usually contains relatively large quantities of gases in solution. These various gases, notably oxygen, which are dissolved in the feed water are liberated in the boilers and 10 other parts of the apparatus under the conditions to which the water is subjected and react on the metal of the various apparatus with the result that pitting and corroding occurs. It is therefore common practice to 15 subject the boiler feed water to a de-gassing treatment before the water is admitted to the boilers in order that the injurious gases may be removed from solution and expelled from the system.

20 Various types of apparatus for deaerating boiler feed water have been proposed. For instance, it has been proposed to deaerate the water in an apparatus consisting of two chambers through which the water passes 25 in series relation. The first of these chambers is a heating chamber and in this chamber the water is heated to a temperature approaching its boiling point under the pressure conditions maintained in that chamber. 30 The heated water from this chamber is then admitted to the second chamber where ebullition occurs either as the result of additional heating steam admitted to the second chamber or as the result of reduced pressure in 35 the second chamber in which latter case ebullition occurs by reason of the contained heat of the liquid. It has also been proposed to deaerate water by dripping it upon a heated surface in which case the liquid is usually 40 sprayed upon a bundle of heating tubes so that the liquid runs over the tube surfaces in the form of a thin film and is heated by reason of its contact with the tubes. Deaeration is satisfactorily accomplished if the liquid to be deaerated is heated to its boiling 45 point corresponding to the pressure under which it is maintained and is then allowed to remain subjected to these conditions for a sufficient length of time to permit 50 all of the contained gases to remove themselves from the solution.

In copending application Serial No. 600, 178, filed November 10, 1922, in the name of Joseph Price and assigned to the present as-

signee, there is disclosed a deaerating apparatus which consists of a containing shell in the bottom of which is maintained a principal body of the liquid under treatment. The water to be deaerated is admitted at the top of the chamber and falls over 55 a series of baffles until it eventually reaches the principal liquid body in the lower part of the apparatus. Heating steam is preferably admitted by means of a perforated pipe submerged in the liquid body so that the 60 bubbling of the steam through the liquid will effect an agitation and will thus assist in bringing the solution to equilibrium and consequently in effecting complete removal of dissolved gases. The present application is 65 in a sense a development and improvement on the apparatus disclosed in this copending application.

In the present apparatus, the liquid is admitted at the upper portion of the unit and 70 falls downwardly through the apparatus over a series of baffles which thoroughly agitate it and distribute it as a rain of falling drops and the liquid eventually accumulates in a principal body of liquid, or a sump 75 in the lower part of the apparatus. A heating unit consisting of a plurality of heat transferring tubes is submerged in the principal liquid body, and heating steam is passed through these tubes at a relatively high 80 velocity. This heating element causes ebullition of the liquid body and thus makes for thorough scrubbing or removal of gases from the liquid body. The major portion of the steam admitted to the heating tubes passes 85 the tubes uncondensed and this steam is then brought into direct contact with the incoming water to thus effect efficient preheating 90 of the water. A slight pressure difference is preferably maintained between the interior of the heating element and the interior 95 of the deaerating chamber to thus insure boiling of the liquid in the lower part of the apparatus.

The accompanying drawings illustrate a 100 preferred embodiment of the invention. In said drawings Figure 1 is a vertical sectional view taken centrally through a deaerating apparatus embodying my invention. Figure 2 is a partial sectional view similar to the 105 lower portion of Figure 1 showing a modified form of heating element. Figure 3 is a view similar to Figure 2 illustrating an au-

omatic pressure control system for regulating the admission of steam to the interior of the shell.

Referring to the drawings, 1 indicates the containing shell or housing of the deaerator in the lower portion of which a principal body of liquid 2 is normally maintained. The incoming water enters at the top of the apparatus through the line 3, and a valve 5 in this line operated through a linkage 7 by means of a float 6 regulates for substantially constant liquid level in the apparatus. The incoming liquid passes down the length of the apparatus over a series of baffles 9. Alternate baffles as shown are provided with central openings and the intermediate baffles are provided with annular passages at their outer edges so that the steam and gases rising through the apparatus assume a tortuous path as indicated generally by the arrows and are thus brought into repeated and intimate contact with the liquid spray descending through the apparatus. The uncondensable gases are drawn out of the apparatus through the vent or discharge line 11. Withdrawal of these gases is preferably effected by means of a steam ejector 12 connected to the line 11 as shown. Deaerated water may be conducted off through the line 13 provided near the bottom of the shell 1.

Submerged in the principal body of liquid in the lower portion of the apparatus is a bank of heating tubes 14. These tubes preferably extend between rigidly spaced headers 15 as shown and are slightly bowed so that by subjection to a material change in temperature, the tubes will flex and will thus loosen and crack off deposits of scale which may have accumulated on them. A trap 16 is provided to conduct off condensate from the discharge header of the tube element. The steam employed in the heating tubes 14 may be derived directly from the boiler or from any other convenient source. The amount of steam admitted to the tubes 14 is such that but a small proportion of it will be condensed in its passage through the tubes. It is conducted through the tubes at a relatively high velocity and thus affords a correspondingly high efficiency of heat transfer.

The steam passing the heat transferring tubes 14 uncondensed enters line 17, from whence it is passed into the interior of the deaerating chamber through the medium of the orifice plate 18. The size of the orifice in the plate 18 is so chosen as to maintain a slight pressure difference between the steam within the tubes 14 and that within the deaerator shell 1. This pressure differential may be from, say, one to five pounds per square inch. In this fashion a slight temperature difference is maintained between the steam within the heating tubes 14 and the water in the shell which difference is suf-

ficient to insure ebullition of the liquid body in the shell with the result that effective scrubbing or mechanical removal of liberated air from the water in the bottom of the shell is accomplished. The steam entering the deaerating chamber through the orifice plate 18 comes immediately into direct contact with the incoming water flowing down over the baffle plates 9.

Ordinarily, all of the steam is passed through the tubes 14 and then into the deaerating chamber through the orifice plate 18 excepting, of course, that portion of the steam which is condensed, and is withdrawn through the trap 16. Under certain circumstances it may, however, be desirable to admit a certain amount of steam directly to the deaerating chamber without first causing it to traverse the heating tubes 14. With this situation, the valve 20 in steam line 19 is opened to a certain extent and a desired amount of steam admitted directly into the deaerating chamber, while at the same time, a desired portion of the steam passes down through the line 21 and enters the submerged heating element 14 after which the uncondensed portion of the steam finds its way through line 17 and orifice plate 18 into the deaerating chamber 1. The valve 20 is a pressure reducing valve designed to maintain in the deaerating chamber a pressure corresponding to that which the orifice plate 18 is intended to regulate. The pressure in the deaerator should be slightly below that in the heating tubes 14, for the purpose of insuring the temperature differential desirable in maintaining a continuous and satisfactory ebullition of the liquid body 2.

For the purpose of affording an efficient heat transfer a high velocity of steam within the heating tubes 14 is desirable. This effect may be enhanced if desired by the provision of a multi-pass heating unit of the type shown in Figure 2. In this figure a two-pass unit is shown, and the steam is caused to travel the length of the unit two times at a relatively high velocity before it is passed along to the line 17 and orifice plate 18. In this figure the heating element is built within the deaerating chamber and is provided with stay rods 22 for the purpose of rigidly spacing the tube sheets so that flexure of the tubes to produce a scale cracking action can be obtained. It is to be understood that this internal type of heating element construction may be employed either with a single pass or a multi-pass unit.

In Figure 3 there is illustrated an automatic valve 23 for maintaining a substantially constant pressure and temperature differential between the submerged heating element and the deaerating chamber. The valve here shown is a diaphragm valve having lines 24 and 25 communicating respectively with the pressure in the deaerating

chamber and the pressure in the submerged heating element so that the valve will regulate for constant pressure differential with the result that a substantially constant temperature differential will also be maintained.

The apparatus of this application therefore affords a simple and inexpensive construction which insures thorough heating of the water under treatment to effect liberation of dissolved gases and a thorough scrubbing or mechanical agitation of the water to insure removal of these liberated gases from the liquid body. The heating is accomplished both through the medium of the submerged heating element and through the medium of the steam admitted to the deaerating chamber into direct contact with the incoming finely divided liquid. The mechanical agitation of the liquid body is accomplished by reason of the ebullition of the liquid effected due to the submerged heating element. This action is aided by reason of the pressure differential maintained between the interior of the submerged heating element and the deaerating chamber.

I claim:

1. Deaerating apparatus comprising a containing shell, means for normally maintaining a body of liquid in the lower portion of said shell, means for admitting incoming liquid above said body of liquid and allowing it to fall under the influence of gravity into the lower portion of the shell, a heating element submerged in the liquid within said shell, means for supplying heating steam to said element, means for supplying heating steam to the said containing shell above the liquid level therein and means for maintaining a temperature differential between said submerged heating element and the space within said shell whereby ebullition of the said liquid body is insured.

2. Deaerating apparatus comprising a containing shell, means for normally maintaining a body of liquid in the lower portion of said shell, means for admitting incoming liquid above said body of liquid and allowing it to fall under the influence of gravity into the lower portion of the shell, a heating element submerged in the liquid within said shell, means for supplying heating steam to said submerged heating element to effect ebullition of the liquid within said shell, means for conducting steam passing said heating element uncondensed into the containing shell above the liquid level therein and means for maintaining a pressure differential between the said submerged heating element and the said containing shell.

3. Deaerating apparatus comprising a containing shell, means for normally maintaining a body of liquid in the lower portion of said shell, means for admitting incoming liquid above said body of liquid and allowing it to fall under the influence of gravity

into the lower portion of the shell, a heating element submerged in the liquid within said shell, means for supplying heating steam to said submerged heating element to effect ebullition of the liquid within said shell, 70 means for conducting steam passing said heating element uncondensed into the containing shell above the liquid level therein and means for maintaining a pressure differential between the said submerged heating 75 element and the said containing shell comprising a valve interposed between the discharge end of said submerged heating element and the interior of said containing shell, said valve being actuated according to so the pressure differential between said heating element and said shell.

4. Deaerating apparatus comprising a containing shell, means for normally maintaining a body of liquid in the lower portion of 85 said shell, means for admitting liquid to be treated above said body of liquid, a heating element submerged in the body of liquid within said shell, means for passing steam through said heating element at relatively 90 high velocity and means for passing into the deaerating chamber, above the level of said liquid in the lower portion of said shell, all of the steam issuing from said heating element uncondensed. 95

5. Deaerating apparatus comprising a shell, means for normally maintaining a body of liquid in the lower portion of said shell, means for admitting liquid to be treated above said body of liquid and allowing it to fall under the influence of gravity into said principal body of liquid, a submerged heating element in the lower portion of said shell, means for supplying a portion of the heating steam directly to the containing shell above the level of liquid therein, means for supplying the remainder of the heating steam to said submerged heating element and means for admitting to the containing shell the steam passing said submerged heating element uncondensed, pressure regulating means being provided for maintaining a temperature differential between said submerged heating element and the space within the containing shell to thereby insure 100 105 110 115 ebullition of the said body of liquid.

6. Deaerating apparatus comprising a shell, means for normally maintaining a body of liquid in the lower portion of said shell, means for admitting liquid to be treated above said body of liquid and allowing it to fall under the influence of gravity into said body of liquid, a submerged heating element in the lower portion of said shell, means for supplying a portion of the heating steam directly to the containing shell above the level of liquid therein, means for supplying the remainder of the heating steam to said submerged heating element and means for admitting to the containing shell the 120 125 130

steam passing said submerged heating element uncondensed, pressure regulating means being provided for maintaining a temperature differential between said submerged heating element and the space within the containing shell to thereby insure ebullition of the said body of liquid, said means comprising a conduit having pressure

reducing means therein whereby a temperature differential is maintained between the fluid in said heating element and the vapor space above said body of liquid sufficient to permit ebullition thereof.

In testimony whereof I affix my signature,

RUSSELL C. JONES.
